LIGHT AND SOUND SIGNALING SYSTEM

John Hays Hammond, Jr., Gloucester, Mass.

Application May 14, 1938, Serial No. 207,871

1 Claim. (Cl. 177—329)

This invention relates to signaling systems and more particularly to an improved system in which a light and a sound signal are produced simultaneously.

An object of the invention is to combine the unusual running light of a vessel with a brilliant, penetrating fog light.

Another object is to provide an improved and efficient fog light.

Another object is to provide a combined fog light and sound signal.

The invention also consists in certain new and original features of construction and combinations of parts hereinafter set forth and claimed.

Although the novel features which are believed to be characteristic of this invention will be particularly pointed out in the claims appended hereto, the invention itself, as to its objects and advantages, the mode of its operation and the manner of its organization, may be better understood by referring to the following description, taken in connection with the accompanying drawing forming a part thereof, in which

Fig. 1 illustrates diagrammatically one embodiment of the invention; and

Fig. 2 shows a modification thereof.

Like reference characters denote like parts in the several figures of the drawing.

In the following description and in the claims parts will be identified by specific names for convenience, but they are intended to be as generic in their application to similar parts as the art will permit.

I have found that an overvoltage light, such as a "photoflood light" produces rays which are extremely penetrating and can be seen in a fog for long distances. These lights are designed to burn at a given normal brilliance when energized at a standard voltage but burn with intense brilliance when operated at an overvoltage, the intensity increasing approximately as the cube of the energy supplied to the lamp. They are, however, capable of operating at such overvoltage for short periods only.

I accordingly utilize an overvoltage light as a combined running light and fog light, energizing the same normally at the constant voltage for which the light is designed to produce a low intensity running light. For fog signal purposes I apply an overvoltage to the light for short intervals to produce flashes of great brilliance which are effective in penetrating fog. I also utilize the overvoltage source to energize a sound signal so that the latter operates simultaneously with the light flashes.

Referring to the embodiment of the invention shown in the accompanying drawing and more particularly in Fig. 1, a source of illumination 11 is provided, which may be a lamp of the photoflood type, above mentioned, which gives an intense illumination in which the longer and fog penetrating wave lengths predominate, with a short life at normal voltage, but which will give a normal illumination with a long life at a reduced voltage. The lamp 11 may be mounted in any suitable housing 12 which is shown as being provided with a Fresnel lens system 13 of usual construction.

The lamp 11 is connected through a switch 15 to one side of a source of power, such as a battery 16, and to a contact 17 of a key 18. This key is made of conducting material and is at all times connected to the other side of the battery 16. A back contact 19 of the key 18 is connected through a resistor 20 to one blade of the switch 15.

A sound producing means such as an electric siren 21 is connected through a switch 22 to one side of the battery 16 and to a third contact 23 of the key 18.

In the operation of the system, with the switches 15 and 22 closed the lamp 11 will give a normal illumination at a reduced voltage due to the drop in voltage produced by the current passing through the resistor 20. This light may be used as one of the standard running or riding lights of the vessel and at this reduced voltage will have a normal long life.

When it is desired to produce a signal, the key 18 is operated for a brief interval, thus disconnecting the resistor 20 and connecting the lamp 11 directly across the battery 16. This causes the lamp 11 to produce a high intensity of illumination which is capable of penetrating a dense fog for a long distance. At the same time a circuit is closed from the battery 16 to the siren 21 which causes it to emit an audible fog signal.

Referring to the modified form of the invention shown in Fig. 2, the lamp 11, casing 12, lens 13, switch 15, battery 16 and contact 17 are the same as those shown in Fig. 1. In this case, however, the key 18 is replaced by a lever 25 which is made of conducting material and is provided with a handle 26 of insulating material.

A whistle 27 is provided and is supplied with compressed air or steam from any suitable source not shown, by a pipe 28. The supply of compressed air or steam is controlled by a valve 29, the arm of which is connected by a rod 30 to the handle 26.

In the operation of this modified form of the invention, when the switch 15 is closed the lamp 11 will be constantly energized to provide a normal illumination, as already described. When the lever 25 is operated the resistor 20 will be disconnected and the lamp 11 will receive the full voltage of the battery 16, thus causing it to be intensely illuminated for a brief interval. At the same time the valve 29 will be opened causing the whistle 27 to be sounded.

Although the light would have a short life if operated continuously at the overvoltage, the present system, which applies the overvoltage only at intervals, utilizes the penetrating effect of the light without greatly reducing its useful life.

Although only a few of the various forms in which this invention may be embodied have been

shown herein, it is to be understood that the invention is not limited to any specific construction but may be embodied in various forms without departing from the spirit of the invention or the scope of the appended claim.

What is claimed is:

A combined fog signal system and running light for a vessel, comprising an incandescent lamp of the photoflood type normally operating on a given normal voltage and having the characteristic of producing an intense light having great fog penetrating power when energized at a given overvoltage, means normally energizing said lamp at said normal voltage to constitute a usual running light of the vessel, and means selectively energizing said lamp at said overvoltage for signaling purposes.
